PROTECTIVE STRIPS FOR FOUNDATION GARMENTS

George G. Wanish, Cortland, N. Y.

Application January 21, 1953, Serial No. 332,469

2 Claims. (Cl. 2—36)

This invention relates to new and useful improvements in girdles and other foundation garments.

More particularly, the present invention proposes the construction of an improved protective shield or strip for disposal beneath the closure means on a girdle or other foundation garment to prevent pinching of the wearer's skin as the garment is fastened.

Another object of the present invention proposes forming the protective shield or strip of stiffly flexible material to provide a firm backing for ease in closing and opening the fastening means on a girdle or other foundation garment and yet permit the necessary bending of the garment.

Still further, the present invention proposes constructing the protective shield or strip with an outer cover of soft flannel or felt material or the like disposed against the skin of the wearer on the garment to prevent any rubbing or rough seams or tapes adjacent to the fastening means.

As a further object, the present invention proposes arranging the protective shield or strip elements so that a single stiffener sheet will be encased in a cover sheet having an adhesive coated inner surface and a flannel or felt coated outer surface.

The present invention further proposes a novel arrangement of a protective shield or strip having its component parts sewn together and attached by stitches to the edge of a corset or other foundation garment bearing the clasps and posts for fastening as an integral part of that edge and disposed beneath the eyes and next to the wearer's skin to permit hook engagement of the eyes without gouging or pinching the wearer.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a front view of a girdle, partly fastened, with parts broken away illustrating the present invention.

Fig. 2 is a similar view showing the girdle fasteners completely opened.

Fig. 3 is a cross-sectional view taken on line 3—3 of Fig. 2.

Fig. 4 is a front view partly broken away, of the protective shield or strip shown in the several figures.

Fig. 5 is a view similar to Fig. 4 but illustrating a modification of the present invention.

Fig. 6 is a view similar to Fig. 2 but illustrating a further modification of the present invention.

Referring more particularly to the drawings, in the first form of the invention illustrated in Figs. 1 to 4, inclusive, a foundation garment in the form of a corset or girdle 15 consists of a body encircling member 16 made in two pieces 17 and 18 laced together in the back by laces 19 with dependent stocking securing straps 20.

The body encircling member 16 has two free edges 21 and 22 which form the customary two adjacent edges of the "coat" style foundation garment shown.

2

Spaced posts 23 and eyes 24 are secured to member 16 adjacent the free edge 22 and like spaced clasps 25 and hooks 26 are similarly secured to member 16 adjacent the other free edge 21 to provide closure means and coacting closure elements.

Garment 15 also has elastic portions 27 and 28 and stays 29 with wide stays 30 disposed adjacent the free edges 21 and 22. The two pieces 17 and 18 of member 16 are similarly constructed and stays 29 are secured by a superposed casing 31 sewn by stitches 32 to the rear or inner side of each piece (see Fig. 3).

The structure of the garment along each free edge 21 and 22 is generally the same. As shown in Fig. 3, free edge 22 has front and rear fabric members 33 and 34, respectively, each sewn along one side margin to piece 18 of body encircling member 16 with one of the wide stays 30 between them. The other side margin of each of the fabric members 33 and 34 is secured to a protective shield or strip 35 as by stitches 36.

Protective shield strip 35, in this form of the invention extends the full length of the free edge 22 of the garment having one of its side edges secured to free edge 22 in the manner just described and disposed to underlie the closure means when the closure elements on the two free edges 21 and 22 are engaged and being engaged.

The shield 35 has a stiffener member 37 of stiffly flexible material such as, for example, drill buchram and a cover 38 of more flexible material. Preferably the cover 38 consists of a single sheet of fabric wrapped or folded around the stiffener strip 37 completely encasing it and secured to it by spaced longitudinal or lengthwise stitches 39. The cover 38 has a soft nap-like outer surface 40 as, for example, of flannel. The cover 38 may, however, be formed of two sheets, one covering each side of the stiffener strip 37 and sewn to it.

It is apparent that the protective shield forms a rigid enough backing to assist in the fastening and unfastening of the posts 23 and clasps 25 and the hooks 26 and eyes 24, as well as providing means to prevent pinching of the wearer's skin in the fastening and unfastening of these elements.

The modification illustrated in Fig. 5 is characterized by the provision of an adhesive backing 41 on the cover sheet 42 of protective shield 35' which is folded over and permanently adhered to stiffener strip 43. In this form, no stitches or sewing is necessary.

In the modification of the invention illustrated in Fig. 6, a foundation garment such as corset or girdle 44 having free edges 45 and 46 with hooks 47 and clasps 48 on free edge 45 and eyes 49 and posts 50 on free edge 46 is provided with a protective shield or strip 51 which extends only partially the length of free edge 46 and is secured to it. In this manner, the protective strip 51 is limited to the upper portion only of the edge 46 of the body encircling member 52 of garment 44 to which it is secured, this being the region where pinching is most likely to occur in fastening the garment. The garment 44 may have front laces 52 to one side of the free edges or may be made without this adjustable feature.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A foundation garment comprising a body encircling member having two free edges, coacting closure elements secured to the member adjacent said edges, a narrow, elongated protective shield strip secured to the member

beneath one of said edges and extending from said edge to underlie the other edge when the two edges are adjacently disposed for operation of the closure elements, said shield strip having an inner stiffener member covered by a covering sheet permanently secured to the stiffener member, said stiffener member being a strip of stiffly flexible fabric material and said covering sheet being a fabric sheet more flexible than the stiffener member and having an outer soft nap-like surface and an adhesive inner surface whereby it is secured to the stiffening member, said protective shield strip being limited to the upper portion only of the edge of the body encircling member to which it is secured.

2. A foundation garment comprising a body encircling member having two free edges, coating closure elements secured to the member adjacent said edges, a protective shield strip secured to the member beneath one of said edges and extending from said edge to underlie the other edge when the two edges are adjacently disposed for operation of the closure elements, said shield strip having

15
20

an inner stiffener member covered by a one piece covering sheet folded over the stiffening member and having an adhesive inner surface whereby it is permanently secured to the stiffener member, said stiffener member being a strip of stiffly flexible fabric material and said covering sheet being a fabric sheet more flexible than the stiffener member and having an outer soft nap-like surface, the body encircling member comprising, at said one edge, front and rear fabric members enclosing one elongated edge of the shield strip, and means securing the fabric members and shield strip together along said one edge of each.
